UNITED STATES PATENT OFFICE.

HARTLEY B. PRATT, OF BARROW-IN-FURNESS, ENGLAND, ASSIGNOR TO VICKERS
LIMITED, OF WESTMINSTER, ENGLAND.

SUBMARINE MINE.

Application filed May 3, 1923. Serial No. 636,295.

To all whom it may concern:

Be it known that I, HARTLEY BLYTH PRATT, a subject of the King of Great Britain, residing at Naval Construction Works, 5 Barrow-in-Furness, in the county of Lancaster, England, have invented certain new and useful Improvements in or Relating to Submarine Mines, of which the following is a specification.

10 This invention relates to submarine mines of the kind which comprise a flotation chamber, a mine proper, an anchor or sinker containing a drum on which is wound a mooring cable which connects the sinker to the flotation chamber and a plummet or sounding ball connected by a line or chain to a pawl or the like adapted to engage with ratchet teeth on the cable drum of the sinker, the weight of the plummet being adapted 20 to hold the pawl out of engagement with the ratchet teeth during the descent of the anchor in the water so as to allow the mooring cable to unwind, and the plummet on touching the sea bed being adapted to allow 25 the pawl to engage with the ratchet teeth so as to stop the continued unwinding of the mooring cable; the sinker then drawing the flotation chamber beneath the surface of the water until it assumes a depth predetermined by the length of the line connecting 30 the plummet to the pawl.

When the flotation chamber requires to be anchored at different depths beneath the surface of the water the length of the plummet line of each mine has to be correspondingly increased or decreased and it is the chief object of the present invention to provide improved means for readily and accurately varying the effective length of the plummet line for any depth between the minimum and maximum determined by the full length of the plummet line. Other objects are to simplify the construction of the sinker casing; to provide improved means 45 for releasing the flotation chamber from the sinker after launching of the mine and to allow the displacement of the sinker to be increased so as to render the same suitable for use in cases where a larger flotation 50 chamber is used containing a heavier explosive charge.

According to one feature of the present invention adjustable means are provided which, when set for any required effective 55 length of plummet line, act automatically

to stop the continued unwinding or paying out of the plummet line when the desired length of plummet line has been unwound.

To this end the plummet line may be wound upon a reel carried by or attached 60 to a screw threaded shaft which carries a displaceable device, adapted, when the reel and shaft rotate, to travel axially along the shaft, the arrangement of the parts being such that when the nut has been displaced 65 to an extent corresponding to a predetermined length of plummet line the nut abuts against a device which stops the continued unwinding of the plummet line. By setting the displaceable device at different distances along the shaft the effective length 70 of plummet line can thereby be varied as desired.

According to a further feature of the present invention, and in cases where the 75 plummet, sinker and flotation chamber are initially held together so as to constitute a single launching unit, means may be provided, actuated by the said displaceable device for releasing any of the usual devices, 80 (such as a pivoted hook which engages one end of a cable connected to or surrounding the mine) which normally act to hold the flotation chamber in contact with the sinker until after launching of the mine. 85

The said displaceable device may be constituted by an internally screw threaded nut or collar provided with a projecting arm or lever, the outer end of which is located 90 within a guide piece, which may be of channel cross section, so as to prevent the nut rotating with the shaft. In cases where the said displaceable nut is also adapted to effect the release of the flotation chamber from the sinker a pivoted lever is provided 95 above the aforesaid fixed collar, one end of the said lever being adapted to engage a pivoted hook which serves to maintain the flotation chamber in position on the sinker, and the other end being disposed in such 100 position relatively to the arm on the adjusting nut that it is adapted to be struck thereby when the nut reaches and abuts against the collar on the screw threaded shaft. 105

In order that the said invention may be clearly understood and readily carried into effect the same will now be described more fully with reference to the accompanying drawings, which show by way of example 110

one constructional form of the said invention and in which:—

Figure 1 is an elevation, and

Figure 2 a partly diagrammatic end view.

5 Figure 3 is a transverse section taken in the way of the depth setting gear.

Figure 3^a is an enlarged view showing a detail of the clutch mechanism, the clutch being shown in the withdrawn position and 10 the handle in position thereon for depth setting purposes.

Figure 3^b is a detail view of the hinged plate by which access is obtained to the clutch for depth setting purposes.

15 Figure 4 is a sectional elevation and

Figure 5 is a sectional plan view.

A is the casing which is constituted by a single rectangular box having a flanged base plate A¹. The top of the casing is provided with a flanged flat plate A², and the flotation chamber or mine proper B is supported on brackets C bolted to the top plate A². The side plates D carry the bearings for the mooring rope and the depth reel gear. The sides of the casing A are closed by dished plates E, which enclose all the gear located outside the side plates D and handles E¹ are provided on the plates E to facilitate removal of the side plates E to 30 permit access to the inside of the sinker. The rail rollers A³ are of the usual standard size and rail gauge. The mooring rope drum F is of cast iron provided with stub shafts F², P¹ on each end thereof. In the 35 example shown the drum is adapted to hold 1500 feet of 1" cir. mooring rope G. The plummet wire reel H in the example shown is adapted to hold 215 feet of wire J, and the arrangement and construction of the 40 depth setting gear is such as to enable the mechanism to be set accurately to correspond to any depth of submersion of the flotation chamber from 5 feet up to the 215 feet. The wire J is coiled on the reel H and 45 from there the free end passes through a hole a in the base plate A and is connected to the plummet K. The reel H is bolted to the sleeve L and is coupled to the screw shaft M by means of a removable clutch 50 piece N. Owing to this arrangement and when the plummet is released the wire is unwound from the reel J which causes the shaft M to rotate with it. As the shaft M rotates the striking lever P travels along 55 the screwed shaft, the lever P being prevented from rotating by the guide channel piece Q (Figure 4). When the striking lever P nears the end of the screwed shaft M it leaves the channel guide Q but is still 60 prevented from rotating with the shaft by a spring controlled lever stop S, until it abuts hard up against the collar R which is rigidly secured to the shaft M. The lever P then rotates with the shaft M and passes 65 the lever stop S. After rotating a quarter

of a turn it strikes and lifts the mine release lever T which releases the mine release hook V, the latter in turn releasing the flotation chamber from the sinker in the usual manner. The striking lever P then strikes and 70 is stopped by the pawl lever W which is freely mounted in the shaft M and the weight of the plummet acting through the reel H, the shaft M and the levers P and W, holds the pawl X out of engagement with 75 the mooring rope drum ratchet plate F.

When the plummet reaches sea bottom its weight no longer serves to hold back the pawl X, and the pawl spring U through 80 the lever W pushes the pawl X into engagement with the ratchet F¹ and the mooring rope drum is locked in the usual manner.

The depth setting of the plummet wire is determined by the initial position at which the striking lever P is set on the screwed shaft M, and consequently the number of turns taken by the shaft M to screw the lever P along to the collar R. A definite length of wire corresponding to the number of turns taken by the shaft M is therefore 90 pulled off the reel J.

With the screw pitch and diameter of reel H shown on the drawing, one complete turn of the shaft M corresponds to 1 metre of 95 wire wound off the reel and a movement of the lever P along the shaft M of $\frac{1}{4}$ inch.

In order to set the striking lever P for the depth setting required the cover plate a is opened and the spring end b of the clutch piece N then protrudes thus enabling the clutch piece N to be gripped and withdrawn. The shaft M is thereby uncoupled from the sleeve L to which the depth wire reel H is bolted. A handle c is then inserted through the hole in the side plate E and coupled to the shaft M as shown at Figure 3^a of the drawing. The handle is first turned to the left so as to bring the lever P hard up against the collar R as a starting point. The handle c is then rotated to the right and the required number of turns given to set the mechanism for the required depth, as shown by an index plate. On the handle c being withdrawn and the clutch piece N replaced, the depth reel is recoupled to the 105 screwed shaft, and the cover plate a is then reclosed.

If it is required to rewind the depth wire on the reel the clutch piece is removed as described above and another handle used 110 which engages the clutch teeth on the sleeve L.

The plummet K, which is of spherical formation, is located within a casing K¹ 115 formed within the sinker, the casing K¹ being open at its lower end. The plummet K is suspended from a release lever Y which latter is connected by a cross shaft e provided at one end with levers f, f and a connecting rod g to a lever h, which latter in 120

turn is connected to a fifth wheel *j* in the sinker. The shaft *e* at its other end is coupled by a lever *f* to a dashpot *Z*, and the plummet release is effected by the fifth wheel in the usual manner after the sinker leaves the launching rails.

Subsidiary anchors *k* formed of bent plate of the shape shown are also provided having cast iron weights *l* bolted thereto.

- 10 Previous to laying, the anchors *k* are retained in the position shown by locking pins *m* which are connected by a length of wire *m*¹ to the flotation chamber *A*. After launching and when the mine is released from the 15 sinker the pins *m* are withdrawn automatically to allow the anchors to fall into working position. If desired readily shearable pins may be provided which are ruptured on the flotation chamber separating from the 20 sinker. The auxiliary wires *n* hold the anchors *k* in the best position for engaging with the sea bed, and the anchors *k* are so coupled to the sinker that they are equally effective for sideways dragging of the 25 sinker.

A gear oil pump brake *I* is shown on one end of the mooring rope drum shaft, the braking action being effected by resistance pressure which can be adjusted as desired 30 by blocking the passage from the delivery to the suction side of the pump. A spring friction brake *O* may also be applied as shown to the plummet wire reel *H*.

The dished side plates *E* increase the displacement of the sinker and this increased displacement allows the weight of the sinker to be increased while retaining the same buoyancy of the combination.

What I claim and desire to secure by Letters Patent of the United States is:—

1. A submarine mine comprising a flotation chamber, a sinker, a mooring cable connecting said sinker to said flotation chamber, a drum within said sinker on which said mooring cable is wound, a plummet, a line connecting said plummet to said sinker the weight of said plummet being adapted to unwind said plummet line, a device which is displaced during the unwinding of said 45 plummet line, adjusting means for altering the initial starting position of said displaceable device, and locking means for the mooring cable drum which are released by said displaceable device when a predetermined 50 length of plummet line is unwound so as to allow said mooring cable to unwind and the flotation chamber to separate from the sinker. 55

2. A submarine mine comprising a flotation chamber, a sinker, a mooring cable connecting said sinker to said flotation chamber, a drum within said sinker on which said mooring cable is wound, locking means for said mooring cable drum, a plummet, a 60 plummet line, means connecting said plummet 65

met line to said mooring cable locking means, comprising a device which is displaced during the unwinding of said plummet line, said plummet when a predetermined length of plummet line has been unwound being adapted to release said mooring cable locking means so as to allow said mooring cable to unwind and the flotation chamber to separate.

3. A submarine mine comprising a flotation chamber, a sinker, a mooring cable connecting said sinker to said flotation chamber, a drum within said sinker on which said mooring cable is wound, locking means for said mooring cable drum, a plummet, a 70 plummet line, the weight of said plummet being adapted to unwind said plummet line, means for connecting said plummet to the mooring cable locking means comprising a device which is continuously displaced during the unwinding of said plummet line, the weight of said plummet when a predetermined length of plummet line is unwound being adapted to unlock said mooring cable locking means so as to allow said mooring cable to unwind and the flotation chamber to separate from the sinker and adjustable means for varying the initial starting position of said displaceable device.

4. A submarine mine comprising a flotation chamber, a sinker, a mooring cable connecting said sinker to said flotation chamber, a drum within said sinker on which said mooring cable is wound, locking means for said mooring cable drum, a plummet, a 75 plummet line, the weight of said plummet being adapted to unwind said plummet line, means for connecting said plummet to the mooring cable locking means comprising a device which is continuously displaced during the unwinding of said plummet line, the weight of said plummet when the plummet line is unwound being adapted to unlock said mooring cable locking means so as to allow said mooring cable to unwind and the flotation chamber to separate from the sinker, and adjustable means for varying the initial starting position of said displaceable device, the weight of said plummet on reaching the sea bed being taken off said plummet line so as to allow the pawl to re-lock the mooring cable drum and cause the sinker to pull the flotation chamber to a depth below the surface of the water corresponding to the length of plummet line which has 110 been unwound.

5. A submarine mine comprising a flotation chamber, a sinker, a mooring cable connecting said sinker to said flotation chamber, a drum within said sinker on which 115 said mooring cable is wound, a plummet, a line connecting said plummet to said sinker, the weight of said plummet being adapted to unwind said plummet line, a screw threaded shaft within said sinker, a dis- 120

- placeable device mounted upon said shaft and adapted to be continuously displaced during the unwinding of said plummet line, adjusting means for altering the initial 5 starting position of said device upon said screw threaded shaft and locking means for the mooring cable drum which are released when a predetermined length of plummet line is unwound so as to allow said mooring 10 cable to unwind and the flotation chamber to separate from the sinker.
6. A submarine mine comprising a flotation chamber, a sinker, a mooring cable connecting said sinker to said flotation chamber, a drum within said sinker on which said mooring cable is wound, a plummet, a line connecting said plummet to said sinker, a device which is continuously displaced during the unwinding of said plummet line, 15 locking means for the mooring cable drum which are released when a predetermined length of plummet line is unwound so as to allow the mooring cable to unwind and the flotation chamber to separate from the sinker, adjusting means for altering the initial 20 starting position of said displaceable device, a projecting arm connected to said displaceable device, a guide piece, the outer end of said projecting arm being located within 25 said guide piece so as to prevent rotation of the displaceable device.
7. A submarine mine comprising a flotation chamber, a sinker, a reel, a screw threaded shaft upon which said reel is mounted, a line wound upon said reel and connected to said plummet, a displaceable nut mounted upon said screw threaded shaft, adjusting means for altering the initial 30 starting position of said nut, a stop against which said nut abuts to stop the continued unwinding of the plummet line when a predetermined length thereof has been unwound, a projecting arm or lever carried by 35 said nut, means for maintaining the flotation chamber in position on the sinker and means controlled by said projecting arm which operate to release the flotation chamber from the sinker when the displaceable 40
- nut has reached a predetermined position on the screw threaded shaft. 50
8. A submarine mine comprising a flotation chamber, a sinker, a reel within said sinker, a screw threaded shaft upon which said reel is mounted, a plummet line wound upon said reel and connected to said plummet, a displaceable nut mounted upon said screw threaded shaft, adjusting means for altering the initial starting position of said nut, a stop against which said nut abuts to 55 stop the continued paying out of the plummet line when a predetermined length thereof has been unwound, a projecting arm carried by said nut, means for maintaining the flotation chamber in position on the sinker, means actuated by said projecting arm which release the flotation chamber from the sinker when the displaceable nut has reached a predetermined position on the screw threaded shaft, subsidiary anchors 60 pivotally attached to said sinker, means normally holding said subsidiary anchors in contact with the sinker, and means controlled by the separation of the flotation chamber from said sinker for releasing said anchors and allowing the same to fall into 65 operative position. 70
9. A submarine mine comprising a flotation chamber, a sinker, a plummet, a line connecting said plummet to paying out gear in the sinker, releasing means which normally hold said flotation chamber and sinker together so as to constitute a single launching unit, a device which is continuously displaced during the paying out of the plummet line by said paying out gear, adjusting means for altering the initial starting 75 position of said device, an arm carried by said displaceable device, said arm being disposed in such position relatively to the means which hold the flotation chamber 80 and the sinker together as to cause the arm to actuate said releasing means when the displaceable device reaches a predetermined 85 position. 90

H. B. PRATT.
